UNITED STATES PATENT OFFICE

SAMUEL NEITERMAN, OF ROXBURY, MASSACHUSETTS

ATTACHMENT FOR TELEPHONES

Application filed January 2, 1932. Serial No. 584,356.

My invention aims to provide improvements in index, calendar and memorandum pad attachments for telephones.

In the drawing which illustrates a preferred embodiment of my invention:—

Figure 1 is a front elevation view of a telephone set and my improved attachment detachably secured to the telephone set;

Fig. 2 is a section taken on the line 2—2 of Figure 1;

Fig. 3 is a perspective view of one of the detachable members of the attaching means of my improved device; and

Fig. 4 is an enlarged section taken on the line 4—4 of Fig. 2 to illustrate the fact that the socket portion surrounds the projection of the telephone device.

Referring now to the specific embodiment of my invention as illustrated by the drawing, I have shown a novel, simple and relatively inexpensive attachment which is particularly, though not exclusively, adapted for use with that type of telephone set which includes a standard 1 supporting a cradle 2 and a combined transmitting and receiving instrument 3 normally supported in the cradle 2, as best illustrated in Figure 1. The cradle 2 has two sets of spaced projections 4 (Figs. 1 and 2) which afford convenient means for supporting my improved telephone attachment.

The particular attachment illustrated comprises a record member 5 which may be a piece of cardboard or the like and a pair of attaching members 6 formed from metal in any convenient manner and having portions of substantial length secured to the member 5 by rivets 7 or other suitable fastening elements. At the lower end of each of the members 6 I have provided a socket 8 which is adapted to fit over one of the projections 4 of the cradle, as best illustrated in Fig. 2. These socket members 8 are substantially as long as the projections 4 to give as much rigidity as possible to the attachment. These socket members are substantially tubular in form (Fig. 4) and are open at the bottom, thereby permitting them to be slipped over the projections 4 and surround them as illustrated.

The record member 5 may take the form of a calendar, a multi-leaf index, or a memorandum pad, which is conveniently positioned in such a manner that it is located at one side of the cradle 2 and projects above the entire telephone assembly. My improved device is easily and quickly attached and detached and adds a finishing touch to the telephone assembly. It is desirable to form the attaching means 6 in such a manner that the record member 5 has its lower edge spaced laterally from that portion of the instrument (Fig. 2) which lies in the cradle 2 to provide a space sufficient to admit the fingers of the operator during removal and replacement of the instrument 3.

While I have shown a particular attaching member 6 (Fig. 3) for use in supporting the record member 5 and for quick detachable engagement with the projection 4, it should be understood that any other suitable means may be substituted therefor and that the means of attachment to the cradle may vary as to construction and manner of attachment.

My invention is particularly useful because it is readily adapted to be attached to and detached from any existing telephone set of the type already described and without change in the telephone set. Furthermore, the record member 5 (whatever it may be) is easily accessible both as to view and for the purpose of inscription.

While I have illustrated and described a preferred embodiment of my invention, I do not wish to be limited thereby, because the scope of my invention is best defined by the following claims.

I claim:

1. A device for attachment to a telephone instrument of the class described which comprises a member having a substantially tubular portion open at its lower end and constructed to make substantially rigid engagement with a projection of the telephone instrument, a prolongation of a wall of said socket portion and a utility device attached to said prolongation.

2. The combination with a telephone set having a telephone instrument and a cradle.

like support for the instrument, the cradle-like support having upwardly extending projections between which the instrument is received and an attachment comprising a ready reference member and attaching means, the attaching means having a substantially tubular portion open at the lower end and detachably receiving one of said projections and engaging all sides thereof, said attaching means being also constructed to support said reference member in a position out of the normal path of movement of the said instrument.

3. The combination with a telephone set having a telephone instrument and a cradle-like support for the instrument, the cradle-like support having upwardly extending projections between which the instrument is received and an attachment comprising a record member and attaching means secured to the record member, said attaching means providing two spaced socket portions detachably engaged with two projections of the cradle at one side of the telephone instrument thereby to support the record member in a visible position above said cradle-like support without interfering with the removal or replacement of the telephone instrument.

30 In testimony whereof, I have signed my name to this specification.

SAMUEL NEITERMAN.
